UNITED STATES PATENT OFFICE.

HENRY E. CATOR, OF OAKLAND, CALIFORNIA, ASSIGNOR OF TWO-FIFTHS TO STEPHEN A. BYRNE AND ONE-FIFTH TO EDWARD H. MORENO, BOTH OF OAKLAND, CALIFORNIA.

LINEMAN'S TOOL.

1,233,980.

Specification of Letters Patent.

Patented July 17, 1917.

Application filed July 1, 1916. Serial No. 107,126.

To all whom it may concern:

Be it known that I, HENRY E. CATOR, a citizen of the United States, residing at Oakland, in the county of Alameda and 5 State of California, have invented new and useful Improvements in Lineman's Tools, of which the following is a specification.

This invention relates to improvements in linemen's tools, such for instance, as are used 10 for clamps and for wire splicing. Most of the tools ordinarily employed for this purpose comprise two jaw members pivoted together and having on their adjacent and opposite faces grooves or notches of different sizes and shape, which are brought into 15 register when the jaws are moved together or their position reversed by being swung about the pivotal connections.

One of the objects of my invention is to 20 eliminate the necessity of reversing the jaws to bring certain recesses or notches into register by interposing between the working faces of the jaws a coöperating intermediate jaw having registering recesses on 25 notches formed in its opposite faces. Another object of the invention is to provide means for locking the intermediate jaw with 30 relation to either jaw to permit it to move in unison with either jaw and also to provide openings thereon for the reception of tools, etc., as will hereinafter be more fully described.

Further objects will hereinafter appear.

The invention consists of the parts and 35 the construction and combination of parts as hereinafter more fully described and claimed, having reference to the accompanying drawings in which—

Figure 1 is a perspective view of the tool. 40 Fig. 2 is a section on line 2—2, Fig. 1.

Fig. 3 is a section on line 3—3, Fig. 1.

The tool illustrated in the accompanying drawings consists of a pair of jaw members 2 and 3 provided with handle extensions 5 45 and 6 and pivotally connected at the opposite ends by means of a pin 4. Pivotally mounted on the pin, and interposed between the jaws 2 and 3 is an intermediate coöperating jaw 8. The inner working face 50 of the jaw 2 is provided with a plurality of semi-circular shaped recesses or serrations 9 and the coöperating face of the intermediate jaw 8 is provided with similar shaped registering recesses 10. The inner 55 working face of the jaw 3 is also provided

with recesses or notches 11 and the coöperating face of the intermediate jaw is similarly provided with registering recesses or notches 12, which in this instance are graduated in size to permit the tool to be used as a sleeve clamp, the opposite recesses 9 and 10 being employed for clamping ordinary wires of varying sizes. It will, therefore, be seen that the meeting faces formed between the outer jaws and the intermediate jaw are 60 provided with registering transverse recesses which, when the jaws are closed, form lines of transverse perforations. Pivotally mounted on the lower end of the intermediate jaw 8, as at 12, is a latch 13 and secured in each 65 jaw is a pin 14 with which the latch is adapted to be engaged. In the present instance, it will be seen that the latch is swung into engagement with a pin 14 formed on the jaw 3. This locks or secures the intermediate jaw with relation to the jaw 3 and in this manner permits the opposite jaw 2 to be swung about the pivot 4 or to be used as 70 an ordinary wire clamping tool. The pivotal mounting of the latch here shown permits the intermediate jaw to be secured with 75 relation to either coöperating jaw 2 and 3 and in this manner permits the tool to be employed either as a wire clamp or as a sleeve clamp, as occasion may demand. The 80 center portion of the intermediate jaw is in this instance provided with openings 15, 16 and 17, which are employed for various purposes. The opening 15 has a die which may be run over standard size bolts for the purpose of cleaning off galvanizing, which generally follows the threads. The opening 16 permits the insertion of a screw driver and thereby permits the tool as a whole, to act 85 as a lever to turn the screw driver and the opening 17 permits the tool to be placed on the square headed shank of a drill or like tool, serving as a handle or lever to turn same. The tool, as a whole, is furthermore provided with a pivotally mounted link 18 90 to permit it to be suspended from the belt of the mechanic employing same and is also provided with a locking link 19 of the usual construction, to secure the jaws together when they are used to clamp wires, sleeves 95 or the like together or when it is desired to secure the handles 5 and 6 against movement 100 for any other purpose.

A tool constructed as here shown is particularly useful in linemen's work. The pro- 110

vision of the intermediate jaw 8 permits the tool to be used, either as a sleeve clamp or wire clamp, without reversing the positions of the jaws about the pivot 4 and furthermore permits the tool as a whole, to be used as a lever in connection with screw drivers, drill bits and for other purposes. These features are of great importance as they not only permit the tool to be used for a greater variety of purposes but also increase its general efficiency and utility.

The materials and finish of the several parts of the invention may be such as the judgment and experience of the manufacturer may dictate.

I wish it understood that various changes in form, proportions and minor details of construction may be resorted to, within the scope of the appended claims, and that I do not wish to limit myself to the specific design and construction here shown.

Having thus described my invention, what I claim and desire to secure by Letters Patent is—

1. A lineman's tool consisting of a pair of jaws with handle extensions at one end, and having the opposite ends curved toward each other and pivoted together, the inner faces having semicircular shaped recesses formed therein, an interposed member turnable upon the common pivot and having parallel outer faces recessed to meet the recesses of the outer jaws, and closable in alignment with said faces.

2. In a tool of the character described, a

pair of jaws with handle extensions from one end, and having the opposite ends curved toward each other and pivoted together so that the inner faces of the jaws are separated and parallel when the handles are closed, an intermediate member turnable upon the common pivot having parallel sides against which both outer jaws may close, said jaws and intermediate member having semicircular recesses formed in their meeting faces which in the closed position form lines of transverse holes, and a latch by which either jaw may be fixed to the center member and the other jaw opened and closed thereon.

3. A hand tool consisting of exterior jaws with the outer ends curved toward each other, an intermediate member and a common pivot upon which all are turnable, said members having edges formed with registering transverse recesses which in the closed position form lines of transverse perforations, a latch by which either of the outer jaws may be locked to the inner one to permit the line of opening to take place between the inner and the remaining outer jaw, and means for securing all of said jaw members against movement about the pivot.

In testimony whereof I have hereunto set my hand in the presence of two subscribing witnesses.

HENRY E. CATOR.
